PROTECTING DEVICE FOR AMMUNITION.

1,201,642.

Specification of Letters Patent.

Patented Oct. 17, 1916.

Application filed November 29, 1915. Serial No. 64,015.

To all whom it may concern:

Be it known that I, JULIUS SCHIRRA, a citizen of the United States, and resident of Pittsburgh, in the county of Allegheny and State of Pennsylvania, have invented certain new and useful Improvements in Protecting Devices for Ammunition, of which the following is a specification.

This invention relates to improvements in protecting devices especially adapted for protecting the rifling bands of ammunition of relatively large caliber.

The rifling band of projectiles is generally of material readily damaged, and when damaged becomes unserviceable for its purpose. Consequently, it is desirable that such band be protected from damage. Devices for this purpose have heretofore been relatively expensive, and where the number of projectiles to be protected is large, the item of cost of the protecting devices becomes serious, especially in view of the fact that this cost becomes practically a total loss even though it be possible to remove the device without damaging it. This is due to the fact that these devices are generally removed only at the point where the projectile is to be used, and it would be impracticable to collect the devices and return them to the point of projectile manufacture for obvious reasons. The cost of manufacture, therefore, becomes of importance, it being understood, of course, that the device must be capable of providing the desired protection.

The present invention is designed particularly to provide a device of this character which will produce the necessary protection, and which can, at the same time, be manufactured at a low cost, so that the loss is brought to a minimum, it being understood that some form of protecting device is absolutely necessary.

Another feature is the ability to quickly remove the device so as to reduce to a minimum the time required in placing the projectile into service when it is to be used, it being obvious that if a comparatively lengthy manipulation of the device is required, the placing of the projectile into the piece of ordnance will be correspondingly delayed, a delay which may prove serious.

In connection with these features, it is also to be noted that the character of the protecting device becomes of importance during transportation and handling of the

projectile, especially when the number being transported is comparatively large, it being necessary, under such conditions, to bring the projectiles into close proximity in order that a maximum number may be transported, this being especially true in transporting the projectiles from the base of supply to the point of use, generally at a period when time and amount of ammunition being transported are essentials.

To these and other ends, the nature of which will be readily understood as the invention is hereinafter disclosed, said invention consists in the improved construction and combination of parts hereinafter fully described, illustrated in the accompanying drawings, and more particularly pointed out in the appended claims.

In the accompanying drawings, in which similar reference characters indicate similar parts in each of the views, Figure 1 is a view showing diagrammatically a projectile having a protecting device according to the present invention in position thereon, the view being partly broken away in order to more clearly disclose the manner in which the device is applied. Fig. 2 is a section taken diametrically through the device. Fig. 3 is a detailed sectional view on the line 3-3 of Fig. 2. Fig. 4 is a detailed view showing the ends of the strip forming the device in one form of our invention. Fig. 5 is a view similar to Fig. 2 showing a different way in which the ends of the strip are secured together. Fig. 6 is a sectional view taken on line 6-6 of Fig. 5. Fig. 7 indicates a modified arrangement.

The protecting device of the present invention is in the form of a band made of suitable material, a preferred material for the purpose being that known as commercial fiber, a material which is tough, comparatively light in weight, and able to resist rough usage, and at the same time maintain its shape.

The material is in the form of a strip, indicated at 10, of suitable length and width, this strip having one side edge turned or bent inwardly upon itself, as indicated at 11, thus placing this edge on the inner side of the band, where, as indicated in Fig. 1, it provides a supporting shoulder 12 which is adapted to rest upon the upper exposed portion of the rifling band, the device being simply slipped over the end of the projec-

tile until this shoulder contacts with the rifling band, the skirt-like portion extending over the rifling band.

The ends of the strip are secured together to provide a ring-like configuration to the device, the drawing indicating two ways in which this may be provided, that shown in Figs. 2 and 3 providing for ready engagement without the use of rivets or other structure, while Figs. 5 and 6 employ a suitable rivet connection.

In the structure shown in Figs. 2, 3 and 4, the ends of the strip are slotted laterally as at 13, the slit at one end extending from the side edge of the strip opposite that of the slit of the opposite end, the bent over portion 11 being foreshortened a distance sufficient to permit of the ready interengagement of the two ends as indicated.

In the form shown in Figs. 5 and 6, but one end of the strip is slotted, the slit extending inwardly from the end longitudinally of the strip, this arrangement providing two portions, the upper one of which is adapted to extend on the outer side of the other end of the strip, while the other portion extends on the inner side. The upper portion, indicated at 10^a is riveted to the opposite end by a suitable rivet 14, the inner portion of the rivet being covered by the inturned portion 11 of the opposite end. In this case, the inturned part 11 is removed for a distance equal to the length of portion 10^a.

As shown in Figs. 1-6 inclusive, the strip is preferably provided with a bead-like portion 15 which extends in the direction of length of the strip. This bead-like structure provides a portion which projects outwardly beyond the plane of the remaining portion of the device and especially beyond the line of the device skirt, the latter being indicated at 10^b. This bead-like structure is adapted to act to retain the skirt out of contact with any object which may contact with the device under general transportation and handling conditions, thus reducing liability of such contact tending to damage the rifling band through pressure placed on the skirt. This bead-like formation is preferably produced while the band is in its strip form, and as the material of the strip has sufficient body for the purpose, the bead-like conformation will generally be retained, even though it is unsupported. If desired, however, this bead-like conformation may be reinforced by the presence of an element, as in Fig. 7, the element being of suitable material, that shown in this figure being a strand of rope or twine. This particular arrangement increases the projection of the bead and thus places the skirt 10^b a greater distance from the outer line of the bead.

As will be readily understood, the blank from which the band is formed can be

stamped out and easily manipulated to produce the desired shape. Consequently, the cost of manufacture is reduced to a minimum, especially since the device can be practically completed by machinery. In 70 the form shown in Figs. 2-4, the forming of the blank, the inturning of portion 11, and the rolling of the bead (the latter also giving the strip its band-like formation) practically completes the operation. Rolling 75 the bead after the portion 11 has been bent in, produces an effect such as shown for instance at 11^a. It is only necessary then to engage the ends in the manner indicated in Figs. 2 and 3, to complete the band. In 80 this form, each end has an overlapping and an underlying relation to the opposite end.

A substantially similar practice is provided in the construction of Figs. 5 and 6, this construction adding the necessity for 85 riveting the ends by the addition of a suitable rivet, a preferred arrangement being to employ a split rivet inserted from the outer face.

As heretofore explained, the devices are 90 simply slipped over one end of the projectile, contact of shoulder 12 and the rifling band limiting the movement in this direction. The skirt of the device preferably has a slight friction on the rifling band, thus 95 tending to prevent shifting of the device to expose the rifling band. This is rendered possible in the forms of devices illustrated herein, by reason of the fact that the blanks are of uniform size and the projectiles and 100 bands are of an exact size, so that practical assurance is had that each device will present practically the same frictional engagement with the rifling band without requiring material careful manipulation of the 105 device in its manufacture.

The device may be removed by slipping it off the projectile, or, if desired, it may be severed at any desired point, thus releasing 11 it without material delay and without necessity of the use of any special tools.

What I claim is:—

1. A protecting device comprising an annular band-like member having an internal shoulder to support the device in position, 11 the body of said member projecting on opposite sides of the plane of said shoulder to cause a portion of the body to form a skirt adapted to project over the surface being protected.

2. A protecting device comprising an annular band-like member having an internal shoulder to support the device in position, the body of said member projecting on opposite sides of the plane of said shoulder to cause a portion of the body to form a skirt adapted to project over the surface being protected, said shoulder extending in the direction of peripheral length of the member.

3. A protecting device comprising an annular band-like member having an internal shoulder, the body of said member projecting on opposite sides of the plane of said shoulder to cause a portion of the body to form a skirt adapted to project over the surface being protected, said member having a peripherally-extending bead-like conformation projecting outwardly beyond the skirt line. 40
4. A protecting device comprising an annular band-like member having an internal shoulder, the body of said member projecting on opposite sides of the plane of said shoulder to cause a portion of the body to form a skirt adapted to project over the surface being protected, said shoulder extending in the direction of peripheral length of the member, said member also having a peripherally-extending bead-like conformation projecting outwardly beyond the skirt line. 45
5. A protecting device comprising a strip of material having one side portion bent upon itself to form a shoulder spaced from such inturned edge, said shoulder acting to support the device in position, the opposite side portion extending beyond said shoulder and being adapted to act as a skirt relative to the shoulder. 50
6. A protecting device comprising a strip of material having one side portion bent upon itself to form a shoulder spaced from such inturned edge, said shoulder acting to support the device in position, the opposite side portion extending beyond said shoulder and being adapted to act as a skirt relative to the shoulder, and means for securing the 55
- ends of the strip together to form a band-like device. 60
7. A protecting device comprising a strip of material having one side portion bent upon itself to form a shoulder spaced from such inturned edge, the opposite side portion extending beyond said shoulder and being adapted to act as a skirt relative to the shoulder, said member having a peripherally-extending bead-like conformation to provide a face projecting outwardly beyond the skirt line. 65
8. A protecting device comprising a strip of material having one side portion bent upon itself to form a shoulder spaced from such inturned edge, the opposite side portion extending beyond said shoulder and being adapted to act as a skirt relative to the shoulder, and means for securing the ends of the strip together to provide a combined overlapping and underlying relation between such ends. 70
9. A protecting device comprising a strip of material having one side portion bent upon itself to form a shoulder spaced from such inturned edge, the opposite side portion extending beyond said shoulder and being adapted to act as a skirt relative to the shoulder, said strip having a slotted end to permit combined overlapping and underlying relation to the opposite end of the strip. 75

In testimony whereof, I affix my signature in presence of two witnesses.

JULIUS SCHIRRA.
